CLAIM

The ornamental design for a MRI equipment, as shown and described.

DESCRIPTION

FIG. 1 is a front view of an MRI equipment showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof; and,

FIG. 8 is a second perspective view thereof.

The broken lines showing in the views are for the purpose of illustrating portions of the MRI equipment that form no part of the claimed design; the broken lines form no part of the claimed design.
